MUSICAL RHYTHM INSTRUMENT

Agnes Van, 27 Harlem St., Rochester, N.Y. 14607

Filed Feb. 10, 1966, Ser. No. 1,002

Term of patent 14 years

(Cl. D56—1)

FIG. 1 is a fragmentary side elevational view of a musical rhythm instrument, showing my new design; and FIG. 2 is a perspective view thereof, to an enlarged scale.

The side not shown in the drawing is substantially the same as the side shown.

I claim:

The ornamental design for a musical rhythm instrument, substantially as shown and described.
